UNITED STATES PATENT OFFICE

CARL WINKLER, OF BERN, SWITZERLAND, ASSIGNOR TO WINKLOR MATERA & STEREO
A. G., OF GLARUS, SWITZERLAND, A CORPORATION OF SWITZERLAND

DRIVING GEAR OF MACHINES FOR CASTING STEREOTYPE PLATES

Application filed September 17, 1929, Serial No. 393,276, and in Germany September 17, 1928.

My invention relates to improvements in the driving gear of machines for casting stereotype plates of the kind in which the shaft by which the mould is opened and closed through suitable intermediate mechanical elements, such as crank mechanism, is rotated by means of a crank arm fixed on same, with which a second crank is connected which is rotated by a motor.

19 In a drive of this kind the two connected cranks are arranged at such an angle relative to each other that, at the moment in which the mould is opened, the driven crank arm fixed on the shaft is turned through a 13 smaller angle by a larger angular movement of the driving crank.

The advantage obtained by this arrangement is that the matrix is separated from the newly cast plate more gently by the 23 initial slow opening motion of the mould.

This device can be combined with a mechanism for imparting to the driving crank a slower motion at the moment in which the mould is being opened. For this purpose the motor can rotate the driving crank through the agency of two elliptical gears meshing with each other.

In the accompanying drawings the invention is illustrated by way of example.

29 Fig. 1 is a side elevation of a machine provided with my invention a portion of the upper structure being omitted, the mould being shown in the closed position.

Fig. 2 is a similar view showing the mould 23 open.

Figs. 3, 4 and 5 are diagrams showing the essential parts in different angular positions.

The mould consists of the core *a* and bed 29 *b*. The core *a* is carried by a frame *d* pivoted to the furnace walls at *c*, while the bed *b* is moved up and down, guided by the slots *e* in the frame *d*, by connecting rods *f* actuated by the crank shaft *g* in a manner well known in the art. On one end of the crank shaft *g* is fastened a crank arm *h* having a crank pin *h'*, which engages in the slotted arm *i*. The axis *k* of this arm *i* rotates in a fixed bearing *k'* (Fig. 3), while the crank shaft *g* is journalled in the frame *d* swing-

ing about the axis *c*. The slotted arm *i* is rotated by the motor *l* through suitable gearing including the elliptical gears *m*, *n*.

In the position in which the mould *a*, *b* is closed (Figs. 1 and 3) the shaft *g* lies over the axis *k* and the crank pin *h'* is then nearest to the axis *k* of the slotted crank or arm *i*. Consequently by the rotation of the slotted arm *i* the crank arm *h* is rotated slower than in any other angular position. By the rotation of the slotted arm *i* the bed *b* is therefore moved away from the core *a*, slowly at first and then with continuously increasing speed up to the middle of the stroke, in which cranks *h*, *i* arrive at the relative position shown in Fig. 4. Thereafter the speed of the bed *b* decreases again until it reaches the entirely open position (Fig. 2), the corresponding position of the cranks *h*, *i* being shown in Fig. 5. During the opening motion of the mold the frame *d* turns about the axis *c*, so that the crank shaft *g* moves into another position relative to the axis *k*, as shown in Figs. 2 and 5.

In the position illustrated in Figs. 1 and 3, in which the mould is beginning to open, a short radius of the elliptical gear *m* is opposite to a larger radius of the elliptical gear *n*. Consequently, in this relative angular position of the elliptical gears the angular motion of the shaft *k* is least.

The combined actions of the elliptical gears *m*, *n*, slotted arm *i*, and crank arm *h*, at the moment of opening the mould, sum up to such a point that the matrix is very slowly peeled off the cast plate without the total time occupied by the casting operation being increased.

What I claim and desire to secure by Letters Patent of the United States is:

1. A driving gear for opening and closing the mold of machines for casting stereotype plates, comprising in combination a shaft, mechanism connected with said shaft for raising and lowering the mold-bed, a crank, carrying a crank pin, fixed on said shaft, a driving crank connected with said first crank and turning about an axis eccentric to said first shaft and arranged at such an angular position in regard to said first

crank that at the moment of opening the mould a larger angular movement of said driving crank produces a smaller angular movement of said first crank.

- 5 2. A driving gear for opening and closing the mould of machines for casting stereotype plates, comprising in combination a shaft, mechanism connected with said shaft for raising and lowering the mold-bed, a crank, carrying a crank pin, fixed on said shaft, a driving slotted crank arm engaging the pin of said first crank and turning about an axis eccentric to said first shaft and arranged at such an angular position in regard to said first crank that at the moment of opening the mold a larger angular movement of said driving crank produces a smaller angular movement of said first crank.
- 10 15

- 20 3. A driving gear for opening and closing the mold of machines for casting stereotype plates, comprising in combination a shaft, mechanism connected with said shaft for raising and lowering the mold bed, a crank, carrying a crank pin, fixed on said shaft, a driving crank connected with said first crank and turning about an axis eccentric to said first shaft and arranged at such an angular position in regard to said first crank that at the moment of opening the mould a larger angular movement of said driving crank produces a smaller angular movement of said first crank, and elliptical gears meshing together at such an angular position that by the action of said gears the opening of 35 the mould is caused to take place at a still slower rate.

In testimony whereof I have signed my name to this specification.

CARL WINKLER.

CERTIFICATE OF CORRECTION.

Patent No. 1,810,875.

Granted June 16, 1931, to

CARL WINKLER.

It is hereby certified that the name of the assignee in the above numbered patent was erroneously written and printed as "Winklor Matera & Stereo A. G.", whereas said name should have been written and printed as Winklor Matern & Stereo A. G., as shown by the records of assignments in this office; and that the said Letters Patent should be read with this correction therein that the same may conform to the record of the case in the Patent Office.

Signed and sealed this 22nd day of September, A. D. 1931.

(Seal)

**M. J. Moore,
Acting Commissioner of Patents.**
